US0D1062001S

(12) **United States Design Patent** (10) Patent No.: **US D1,062,001 S**
(45) Date of Patent: ** Feb. 11, 2025

(54) **LIGHTING FIXTURE**

(71) Applicant: **Wangs Alliance Corporation**, Port Washington, NY (US)
(72) Inventor: **Emanuel Valera Reyes**, Crestline, CA (US)
(73) Assignee: **WANGS ALLIANCE CORPORATION**, Port Washington, NY (US)

(**) Term: **15 Years**

(21) Appl. No.: **29/910,575**

(22) Filed: **Aug. 22, 2023**

(51) LOC (15) Cl. **26-05**

(52) U.S. Cl. **D26/90**
USPC .....

(57) **CLAIM**

The ornamental design for a lighting fixture, as shown and described.

DESCRIPTION

FIG. 1 is a front perspective view from above of a lighting fixture according to the new design;

FIG. 2 is a rear perspective view from below thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the drawings illustrate portions of the lighting fixture and form no part of the claimed design.

1 Claim, 8 Drawing Sheets
